[57] CLAIM

The ornamental design for a support pad for an infant,
substantially as shown and described.

DESCRIPTION

FIG. 1 is an isometric view showing the top, one end,
and one side of the design;

FIG. 2 is a top view of the design;

FIG. 3 is a view of said one end;

FIG. 4 is a bottom view;

FIG. 5 is a view of said one side, which is a mirror
opposite of the other side; and

FIG. 6 is a view of the other end.

Fig. 3.

Fig. 5.
